UNITED STATES PATENT OFFICE.

GEORGE L. McCALLUM, OF CROSBY, PENNSYLVANIA.

DOOR-HANGER TRACK.

1,111,661.

Specification of Letters Patent. Patented Sept. 22, 1914.

Application filed June 25, 1914. Serial No. 847,310.

To all whom it may concern:

Be it known that I, GEORGE L. McCALLUM, a citizen of the United States, residing at Crosby, in the county of McKean and State 5 of Pennsylvania, have invented a new and useful Door-Hanger Track, of which the following is a specification.

This invention relates to a hanger for sliding doors, and more particularly to the 10 track portion thereof.

The object of the invention is to provide a track in the form of a hollow parallelepiped with the outer and vertical wall extended to form a downwardly extending 15 lip to thus house in a weatherproof manner the door supporting carriage.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 20 the scope of what is claimed, without departing from the spirit of the invention.

In the drawings accompanying this specification and forming a part thereof, the preferred form of my invention is illustrated.

In said drawings:—Figure 1 is a view in perspective of my improved door hanger. Fig. 2 is a view in cross section thereof. Fig. 3 is a view of the channel-like blank 35 used in the formation of the track and prior to the bending of the longer leg.

Referring to the drawings in which similar reference numerals designate corresponding parts throughout the several views, 40 a door 4 is provided with the carriage 5 and mounts the same for sliding movement. The carriage 5 includes the metallic support 6 to which is rotatably secured the wheel 7. The wheel extends substantially central above 45 the door 4 as illustrated in Fig. 2 and thus supports the same in an upright and sliding manner.

The track is formed as a channel iron with unequal legs as illustrated in Fig. 3 and 50 thus may be rolled of any desired length and formed in an economical and practical manner. The channel shown in the said figure includes the legs L and L¹ of unequal lengths and in order to shape the same into the 55 forms illustrated in Figs. 1 and 2, the chan-

nel iron C² is employed and placed in an upright manner against the leg L as illustrated by dotted lines in Fig. 3. The leg L is then bent down against the channel and its extremity is bent upward as at 12. The track 60 as thus formed includes the front and rear walls 8 and 9, and the top and bottom walls 10 and 11. The front wall or apron 9 is bent outward as at 12 to form an outwardly extending lip which prevents rain or snow 65 from entering within the hollow track. The lower wall 11 is relatively shorter than the upper wall 10, thus defining a restricted opening 13 communicating with the hollow interior of the track. The track as thus 70 constructed will be in the form of a parallelepiped or quadrangular prism. This shape in addition to embodying the maximum strength, allows the same to be made of channel iron with unequal legs as described and also provides that they may be conveniently packed in suitable lengths and 75 will occupy a minimum space when piled one upon the other. The channel iron C² is retained within the track and forms a 80 brace and reinforcement for the upper portion thereof. Suitable bolts 14 extend through the channel iron C² and the track and are adapted to engage a door frame or allied structure, and thus slidably mount a 85 door. Suitable end blocks 15 are employed, closing the ends of the track and thus insuring that the entire structure will be weatherproof and may be used in exposed 90 places, such as for the supporting of car doors and other similar structures.

Having thus fully described my invention, what is claimed is:—

A track comprising a channel iron, the upper flange having a depending apron extending across the open front of the channel and defining a slot with the lower flange, a reinforcing member fitting snugly within the channel iron contacting with the upper flange, back plate, and the said apron, and means engaging the said channel iron and reinforcing member, holding the same in rigid relation.

In testimony that I claim the foregoing as my own, I have hereto affixed my signature in the presence of two witnesses.

GEORGE L. McCALLUM.
